Fig. 5

FIG. 1 is an elevational view of a display carton showing my new design, wherein the geometric figure is oval and the cut-out areas are half of an oval; FIG. 2 is a perspective view thereof; FIG. 3 is a perspective view of a modified form of the display carton design wherein the geometric figure is square and the cut-out area is half of a square; FIG. 4 is a perspective view of another modified form of the display carton design wherein the geometric figure is diamond-shaped and the cut-out area is half of a diamond; and FIG. 5 is a perspective view of still another modified form of the display carton design wherein the geometric figure is hexagonal and the cut-out area is half of a hexagon.

The sides opposite those shown in FIGS. 1, 3, 4 and 5 are substantially the same as the sides shown.

The drawings are shaded to indicate contrast rather than any specific colors.

I claim:

The ornamental design for a display carton, as shown and described.
